BOILER CONSTRUCTION

Carington Carysfort Cariss, Brantford, Ontario, Canada, assignor to Waterous Limited, Brantford, Ontario, Canada

Application November 16, 1940, Serial No. 366,018

4 Claims. (Cl. 122—106)

This invention relates to high pressure boiler construction of the fire tube type. Up to the present time high pressure boiler construction in general, though relatively satisfactory, has presented a number of problems in the way of installation, maintenance and operation. In the majority of cases high pressure boilers are very large, heavy and bulky and therefore are difficult to ship to the destination, and also present on this account difficulties in getting them installed. Furthermore, such structures also present difficulties from the point of view of operation and maintenance. Lime and other foreign material have a tendency to settle and cake within the pressure vessel thus reducing its efficiency and making it necessary at frequent intervals to scrape the interior of the vessel through appropriate manholes and handholes. Failure to attend to this frequently and carefully presents a positive danger of damaging the vessel through the bulging and burning of the plate. Moreover the circulation facilities are subject to improvement. These disadvantages are overcome by the present invention.

According to the invention the boiler construction includes a series of waterlegs connected together to form the mounting base for a pressure vessel and enclosing the fire box. The pressure vessel is independent of the base but supported thereon and detachably connected with it by exterior conduits which extend between certain of the waterlegs and the vessel so as to provide for circulation of fluid therebetween. The pressure vessel is therefore detachable from the mounting base and the conduits are designed to form part of the supporting means for it.

Preferably the structure includes auxiliary supports for the pressure vessel of such character as to render the connection flexible in order to compensate for expansion and contraction of the parts during use. The auxiliary supporting means is of simple construction and is such as to protect the vital parts of the waterlegs.

Included in the construction is an outlet conduit communicating with the bottom of the pressure vessel and extending through the waterleg forming the rear wall of the mounting base, the conduit being extended to connect with the rear wall from the outside and functioning to circulate liquid between the pressure vessel and said waterleg and at the same time forming a positive discharge for foreign material entering the pressure vessel.

The construction is such that conduits of large cross sectional area may be employed and pro-

vision may be made for the connection of a pump to the outlet conduit so that circulation of the liquid in the boiler system will be smooth and even.

5. The invention will be clearly understood upon consideration of the following detailed description and accompanying illustrations of its application to a double pass boiler.

In the drawings:

10. Figure 1 is a longitudinal sectional elevation of the boiler construction according to the present invention.

Figure 2 is a front elevation of the boiler construction.

15. Figure 3 is a rear elevation.

Figure 4 is a top plan view.

Figure 5 is an enlarged sectional detail of the type of handhole employed.

20. Figure 6 is an enlarged fragmentary sectional detail of the connection between the pressure vessel and the side waterlegs and also illustrates in detail the means of auxiliary support.

Figure 7 is a sectional detail of an alternative way of connecting the fluid legs to form the connecting base for the pressure vessel.

25. Referring to the drawings, A indicates the boiler construction as a whole, which includes a mounting base B made up of four fluid legs, two side fluid legs 10 and 11, a front fluid leg 12 and rear fluid leg 13. These fluid legs are joined together so as to communicate with one another, and to enclose the fire box of the boiler while the front leg is recessed as at 14 to provide a fire door opening or openings. The base B is designed to support the boiler, pressure vessel or still C and the front fluid leg is preferably recessed as at 15 to accommodate it. The boiler carries two series of fire tubes 16 and 17 so that the products of combustion and hot gases may pass

30. 35. 40. 45. from the rear end 18 of the fire box through the passage 19 normally housing the fire arch through the series of tubes 16 to the head 20 of the boiler and thence by way of the tubes 17 to the smoke box and outlet which is suitably housed at the rear of the boiler above the fire arch.

50. The boiler is connected with the side fluid legs by means of external connections which preferably take the form of arcuate conduits 21 which provide a convenient means for detachably connecting the boiler C to the base B.

The conduits 21 are mounted by forming the boiler and the fluid legs in question with protruding annular pads or bosses 22 and 23 respectively, the conduits being formed with flanges

24 and preferably bolted to the parts 22 and 23. A gasket of metal, asbestos or other suitable material is inserted between the flanges 24 and the parts 22 and 23 respectively, it being important, of course, that the gasket material should be capable of standing the service without leakage.

The conduits 21 are formed of a metal suitable to the circulating material which is designed to pass through them but usually, for manufacturing convenience, they are formed of steel, either cast or forged. It is essential that the conduits 21 and their flanges 24 be relatively heavy in construction as the side connections are so designed as to form the means of carrying the weight of the upper portion or pressure vessel C. At the same time these conduits are designed to be sufficiently flexible to take care of slight variation in relative position of the parts of the structure due to thermal expansion or other movement.

At this point it is well to refer to an auxiliary means of support for the boiler or pressure vessel, which I preferably include in the structure on account of the forces involved and the possibility of damage to life or property in the event of any failure of the connection between the upper and lower portions of the pressure vessel C which is preferably made in two sections. I propose in addition to support the boiler on the base from a point below the upper connection of the conduits 21.

The support takes the form of a heavy angle iron 25, the lower horizontal portion thereof 26 projecting from the side of the pressure vessel over the top of the side fluid legs 10 and 11. The upper and substantially vertical section 27 lies along the side of the pressure vessel and is attached to the latter by means of suitable studs 28 designed to pass through the shell of the pressure vessel and if desired into a reinforcing plate 29 which is welded or otherwise secured along the inside of the pressure vessel C. This latter reinforcing plate may be used, if necessary, to obtain sufficient support for the studs.

As the pressure vessel, when heated or cooled, will change its length relatively to the angle bar or bars 25, the holes in the portion 27 of the latter, through which the studs pass, are elongated or formed in the manner of a slot extending in the longitudinal direction of the pressure vessel which will allow for such expansion.

In those cases where the angle iron or irons 25 are employed to transfer the weight of the pressure vessel C onto the fluid legs making up the base B additional construction is preferably employed. This may take the form of ribs 30 which may be formed from suitable bar section welded along to the upper portion of the fluid leg at each side in spaced apart relation to each other, the ribs projecting above the upper surface of the fluid leg and forming a mounting upon which the portion 26 of the angle iron or irons 25 may bear as clearly shown in Fig. 6. This construction protects the welded joint 31 along the top of the fluid legs.

Thus, in a simple manner the independent pressure vessel C is adequately supported on the base B and in such a manner as to compensate for movement due to expansion and contraction. Moreover, as will be appreciated the connections are of simple character while durable and therefore readily permit the mounting or demounting of the pressure vessels C on its base.

To complete connection between the pressure vessel and its base and prevent gas leakage be-

tween them, asbestos cement or other suitable material 32 is placed between these two parts, as clearly shown in Fig. 6.

The circulatory system between the pressure vessel C and the base B is completed by including a rear circulating connection D. (See Figs. 1 and 3.) The conduit D is connected to the lower rearward surface of the pressure vessel C by means of an annular pad, boss or the like 33 which is riveted or welded around an outlet opening 34 in the pressure vessel. The conduit D is provided with an annular flange 35 which is bolted or otherwise attached to the member 33, the preferred construction including an annular groove in the member 33. The conduit D is bent preferably to project horizontally and rearwardly of the pressure vessel passing through the rear fluid leg 13 by means of a suitable enlarged opening 36 which is preferably of round or oval cross section and packed with asbestos or other soft material 37 in order to prevent gas leakage from the fire box without interfering with the free movement of the conduit. This movement may be due to changes in temperature or slightly relative movement between the pressure vessel C and the fluid leg 13.

On the outside of the fluid leg 13 conduit D terminates in a flanged head 38. The flange 38 is removable in order to permit the conduit to be mounted or removed. This flange may be screwed on the conduit, expanded on or attached by means of welding that can be subsequently chipped off. The removable flange thus obviates the necessity of providing an extremely large opening 36 through the waterleg 13.

The conduit D is designed to connect with the bottom of the fluid leg 13. The exact arrangement of the pipe connections will, of course, depend on the particular conditions prevailing, the important factor being that piping should be of sufficient length and properly arranged to permit a certain amount of flexibility and also to permit clean-out facilities. A suitable arrangement is shown in Fig. 1 wherein a short flanged pipe section 39 is provided, one end being bolted or otherwise fastened to the flange 38 with suitable gasket material therebetween and the other having applied thereon a blank flange 40 in any suitable manner. The pipe section 39 is provided with a side opening flanged as at 41 and to this may be connected a suitable flanged elbow-fitting 42 (see Fig. 3), connected to a flanged pipe section 43. At the bottom of the fluid leg 13 a short flanged pipe section 44 similar to section 39 is secured to a suitable annular pad or boss 45 mounted on the outer surface of the waterleg and surrounding an inlet opening 46 to the interior of this fluid leg. The pipe section 44 at the opposite end is closed by a blank flange 46 while by means of an opening in the side of this section flanged as at 47 and a flanged elbow-fitting 48, the pipe section 44 is connected to the section 43. Thus a circulating path between the lower end of the pressure vessel and the lower end of the fluid leg 13 is provided.

The structure and connection of the conduit D between the pressure vessel C and fluid leg 13 is such as to permit the use of a conduit or pipe system of large cross sectional area which will permit free circulation from the pressure vessel C to fluid leg 13 and owing to the large diameter of this pipe and the free circulation of water or other fluid therein it will remain comparatively cool and cannot be seriously damaged by the hot gases from the fire or other manner of heating,

which necessarily traverse the path of the conduit within the base B. Thus it is not generally necessary to protect the conduit further from these gases.

As an additional precaution, however, against any possible damage due to extreme heats a shielding jacket 49 in the form of a split fitting may be applied on the conduit D to surround it, the two parts of the fitting being peripherally flanged and bolted or otherwise secured together. Suitable internal spacing ribs 50 are provided to form an air channel between the conduit and the jacket.

The jacket is made of suitable heat resisting material usually chromium cast iron bolted together by heat resisting bolts such as stainless steel while the conduit D, for the purpose of manufacturing convenience, may be made of steel casting. It can, however, be forged or otherwise formed of any other desirable material the character of which will depend upon the temperature and pressure to be encountered and also on the nature of the circulating medium, usually but not necessarily always, water.

The connections for the conduit B outside the fluid leg 13 may include blow-off valve 51 while these connections are so designed that a pump can be placed at any convenient point in the external piping. Such pump, where employed, would be designed to stand the maximum working pressure and temperature of the boiler and would be of such a capacity that sufficient water could be circulated to allow a larger output to be produced from the boiler without danger of the fire box portion becoming dry. Such a pump can be of any capacity found desirable but should have a capacity of not less than ten times the normal output of the boiler or pressure vessel. Such device may be used to increase the speed of circulation and to assist in maintaining a uniform temperature throughout the pressure vessel as well as to increase the speed at which the contents of the pressure vessel may be heated without damage.

By locating the conduit D at the bottom of the pressure vessel as shown any scale or foreign material that usually builds up within the vessel and requires constant attention by way of frequent cleaning out through the handholes or manholes is eliminated. This is readily discharged through the conduit D by reason of its position, its large size and the smooth and even flow of fluid through it, the material being finally delivered to the bottom of the fluid leg 13 where it can be cleaned out in the usual manner. It will be apparent that the conduit D and its connections are readily mountable and demountable and easy of access so that on the whole the pressure vessel may be readily separated from the mounting base and vice versa.

An alternative form of construction of the fluid leg system is illustrated in Fig. 7 wherein each fluid leg is independent of the other but connected by means of external pipes or tubes 52 extending from a point adjacent to the marginal edge of each fluid leg to a corresponding point on the adjacent fluid leg. This type of construction obviates the difficulties experienced in making larger water cooled fire boxes for boilers or other devices which becomes a more difficult problem in larger sizes owing to the weight and extreme dimensions that must be handled. Moreover, it is, of course, also difficult to handle such large units in one piece when shipping or installing.

The pipes 52 connecting each separate unit with an adjacent unit may be castings or forgings or may be built up from pipe and to avoid leakage of air and gases between the corners of the sections so united, the corners are packed with high temperature cement 53. This construction, while readily applied to the type of boiler shown in the present application can be used in the construction of locomotive boilers, water tube or practically any type of boiler and may also be employed in stills for process vessels. It will be appreciated that such construction lends itself particularly well to the structure previously described in this application.

15 The construction also incorporates an improved type of handhole illustrated in Fig. 5 for the purpose of cleaning the fire box legs. It is necessary to provide openings that can be readily opened and closed and of sufficient size to permit ready access to the space between the plates of the legs. A new type of handhole is shown as applied to a double curved surface such as the point of juncture between two of the fluid legs although it may be readily adapted to a single curved surface. The construction includes a projecting collar or stub sleeve which is cast or forged to fit the surface of the fluid leg of the boiler. This is attached to the outer plate of the leg by means of rivets 54 which are countersunk into the upper end of the sleeves, the number of rivets depending of course, upon the size of the opening required and the pressure involved. The cover plate 55 is attached to the sleeve 53 by means of suitable studs 56 used in sufficient number and of a size to insure that the cover 55 can be pulled tightly upon the end of the sleeve. A gasket 57 of soft metal, asbestos, rubber or other suitable material capable of withstanding the pressures and temperatures involved is interposed between these two parts. This construction permits ready access to the interior of the fluid leg and provides a strong structure subject to long wear avoiding the possibility of leakage.

45 It is apparent from the foregoing that the construction described removes a number of difficulties existing in the boiler art since it avoids difficulties in shipping large assembled structures as well as difficulty in the installation of such structures. It is obvious, of course, that the pressure vessel and mounting base therefor can be shipped separately and that due to the simple construction for uniting the two parts together it can be easily installed as well as readily dismantled. This structure also is stronger than prior structures wherein the water legs were frequently connected to the pressure vessel thus weakening it as it necessitated cutting away part of the cylindrical circumference of the shell.

50 60 In extremely large structures the use of completely unitary fluid legs independent of one another and joined by exterior circulating connections are of particular advantage as each section may be shipped separately, while the sections also are easily erected and assembled.

65 The circulatory system also presents an advance in the art while the outlet portion of the system readily avoids the difficulty of the accumulation of foreign material within the boiler proper.

70 What I claim as my invention is:

1. High pressure boiler construction comprising water legs forming a mounting base for a pressure vessel, a pressure vessel independent of and supported by said base, detachable external

conduits extending between certain of said water legs and said pressure vessel to circulate fluid therebetween, brackets fastened to the pressure vessel and projecting outwardly therefrom, and bracket supporting means extending along the upper surfaces of certain of the fluid legs and on opposite sides of the center lines thereof, said means projecting above said upper surfaces to support the brackets in spaced relation to said center lines.

2. High pressure boiler construction comprising a series of water legs forming a mounting base for a pressure vessel and enclosing the fire box therefor, a pressure vessel independent of but supported on said base, detachable external conduits extending between certain of said water legs and said pressure vessel to circulate fluid therebetween, said external conduits forming a part of the supporting means for the pressure vessel, brackets fastened to the pressure vessel and projecting outwardly therefrom, and ribs secured to and extending longitudinally of the upper surfaces of certain fluid legs on both sides of the center line thereof and projecting above said upper surfaces to receive said brackets in bearing engagement.

3. In high pressure boiler construction employing a pressure vessel and fluid legs enclosing a

fire box and connected to and supporting said vessel, a fluid outlet comprising a conduit connected to the lower surface of the vessel and extending through the wall of one of said legs near the rear of the fire box, a portion of said conduit extending exteriorly of said leg and connecting therewith near the bottom thereof, to permit flow of fluid from said vessel to said leg, and said leg to which the conduit is connected having a hand-hole therein near the bottom thereof.

4. In high pressure boiler construction employing a pressure vessel and fluid legs enclosing a firebox and connected to and supporting said vessel, a fluid outlet comprising a conduit connected to the lower surface of the vessel and extending through the wall of one of said legs near the rear of the fire box, a portion of said conduit extending exteriorly of said leg and connecting therewith near the bottom thereof to permit flow of fluid from said vessel to said leg, said conduit being formed in detachable sections exteriorly of the water leg including two horizontal sections and a substantially vertical section offset from said horizontal sections to permit relative movement between said pressure vessel and said water leg.

CARINGTON CARYSFORT CARISS.
